TO CHAIN BELT COMPANY, OF MILWAUKEE, WISCONSIN, A CORPORATION OF WIS-
CONSIN.

HOIST FOR POWER LOADERS.

Application filed April 9, 1924. Serial No. 705,271.

This invention relates to loading apparatus in which a vessel that receives the load or charge is periodically moved from a receiving to a discharging position, and the invention has for its object to apply the power that moves said charging vessel to advantage. Our invention is primarily intended for use in connection with a charging or loading skip for a concrete mixer, whose movements are controlled by a cable connected with the skip; although the invention in its useful applications is not limited to the particular use referred to, nor to the specific mechanism which we have shown in the drawings as embodying the invention.

In the accompanying drawings—

Figure 1 is a side view of a loading skip or hopper for a concrete mixing machine, to which our invention is applied, the receiving position of the skip and its associated and cooperating parts, being represented in full lines, the discharging position thereof by dotted lines, and an intermediate position by dot and dash lines.

Fig. 2 is a rear elevation of the apparatus. Fig. 3 is a side elevation of a concrete mixing machine with a loading apparatus embodying the present invention, of somewhat different construction from that shown in Figs. 1 and 2.

Fig. 4 is rear elevation of the apparatus shown in Fig. 3.

In the accompanying drawings, A designates the framework of a concrete mixing machine, the drum of which is designated B. C represents the loading skip or hopper into which, when resting upon the ground or in a lowered position, a charge of materials to be mixed is delivered, and which when moved to the position indicated by dotted lines in Fig. 1, discharges such charge into the drum B. The spout portion c of the skip has secured to its opposite sides the bars D which are pivotally connected, at E, with the frame of the machine. The parts thus far described are well known in the art and serve to locate the pivot of the skip in advance of the nose or forward end of the spout section c thereof.

2, 2, indicate a pair of stifflegs pivotally secured, at 3, to the opposite sides of the frame of the machine, they constituting a boom, and being located such distance apart as to permit the spout section of the loading skip to lie and move between them. At

the upper ends of the stifflegs are supported pulleys or idler sheaves 4 over which pass the cable or cables 5 through which the movements of the skip C are controlled. The cable passes from the pulleys 4, over pulleys 15 located on the upper portion of the framework A and thence to differential winding mechanism located, preferably, on the lower portion of the framework A. This mechanism is represented as comprising a pair of winding drums 6 and a drum 7, of larger size than the drums 6, around which is wound a cable 8 that is secured also to a power driven drum 9 mounted on a shaft 10 geared to a motor or engine. The cable passes from one of the winding drums 6 over idler pulleys 15 and 4 to a side of the skip or loading vessel C, under the same, thence across the opposite side thereof, to and past the idler pulleys 4 and 15, and thence to the winding drum 6 on the side of the machine opposite the first mentioned winding drum. The arrangement just described is employed in view of the large size of the skip and the fact that it is frequently unevenly loaded, making it desirable that the cable 5 should have two strands connected respectively with the skip at its opposite sides. It will be understood that each strand of the cable 5 operates in controlling the movements of the skip, and that if it were arranged at the central longitudinal axis of the skip a single strand of cable would be sufficient.

11, 11 represent links each pivotally connected, at 12, with one of the stifflegs, and at 13, with a bracket or suitable support 14 movable with the skip or loading vessel C. The support 14 is represented as a triangular frame secured to a bar D.

The parts of the loading mechanism being in the positions represented in full lines in Fig. 1, if power be applied to the cable 5, winding it upon the drums 6, it will be drawn across the idler pulleys or sheaves 4 and 15, shortening those portions of the cable between the pulleys and their points of attachment to the skip, thus causing the latter to be lifted and tilted about its pivotal axis E. As the skip moves upwardly toward its discharging position, the frame 14 moves therewith, carrying the pivoted end 13 of the link along the path indicated by the curved line a. This causes the opposite ends of the links, which are pivotally con-

ected with the stifflegs 2, to follow the paths indicated by the curved line *b* and to swing the stifflegs 2 forwardly or in the general direction in which the loading skip 5 is moving, and in advance of the latter, although at a slower speed. The result is that the parts assume successively the positions indicated by the dot and dash lines, and the dotted lines, in Fig. 1. It will be observed 10 that the several parts of the loading mechanism described are so related to each other that the cable 5, when the parts are in the position for loading the skip or vessel C, occupies a line that approximates being tangential to the circle described by the part 15 of the skip to which the cable is attached; in other words, the pull of the cable applies power to lift the skip and its load to the greatest advantage. As the parts assume 20 the intermediate positions between the skip-charging and skip-discharging positions there is some variation in the angular relation of the cable to the skip, but this variation is not great and the force transmitted 25 through the cable to move the skip and its load is always applied to advantage.

It will be seen that in the arrangement described the parts of the mechanism employed for controlling the movements of the skip do not extend much, if any, above the framework A of the machine which is a fact of much practical importance since it permits the machine to be moved into positions that could not be occupied were 5 the supports for the operating cables located at points high above the drum or other operating part of the mechanism with which the loader is associated.

It will also be observed that the pivots 40 3, uniting the stifflegs to the frame, are to the rear of the pivots E of the skip and that the pivotal connections 13 between the links 11 and the skip are located to the rear of the pivots E and in advance of the pivots 45 3; and also that the pivot 13 is at less distance from the pivot E than is pivot 12 from pivot 3. The result of this arrangement is that the stifflegs move through less angular distances than does the skip, and the pulleys 4 which when the skip is in loading position are above the hopper of the skip, and a considerable distance in advance thereof, are but little in advance of the skip when the hopper reaches its discharging position, as represented by the dotted lines in Fig. 1. The path of the pulleys 4 is indicated by the dotted lines *c*.

In Figs. 3 and 4 we illustrate an embodiment of the invention different from that illustrated in Figs. 1 and 2, corresponding parts of the two machines illustrated being designated by the same reference characters. The form of invention shown in Figs. 3 and 4 differs from the other in that the links 11', 60 corresponding with the links 11 of Figs.

1 and 2, are pivotally connected with the stiff legs at 12' and with the skip C at 13', the latter connection taking the place of the connection 13. The movements of the several parts are illustrated in Fig. 3 by full 70 lines, dot-and-dash lines, and dotted lines, the same as in Fig. 1.

What we claim is.—

1. The combination with a tiltable vessel, 75 of a cable connected thereto for operating it, a winding drum for the cable, a guide across which the cable passes in its course from the winding drum to the vessel, a movable support carrying the said guide, and a permanent connection between the vessel and support arranged to cause the support to be shifted simultaneously with the tilting of the vessel and in advance of the latter.

2. The combination with a pivoted vessel, 80 of a cable for operating it, a winding mechanism for the cable, a guide across which the cable is drawn for tilting the vessel, a pivoted support carrying the guide, and a connection between the vessel and the said support arranged to move the latter about its pivot whenever the vessel is moved about its pivot, said connection being arranged to cause the support to move in the same general direction as the vessel moves and simultaneously therewith.

3. The combination with a supporting frame and a loading skip pivotally united thereto, of a cable for controlling the movements of the skip, a winding drum on the frame to which the cable is connected, a support pivoted to the frame and extending above the skip, a cable guide carried by the upper portion of the said support, across 100 which the cable passes, and a rigid connection pivotally united to both the skip and the support arranged to cause the said support to be shifted whenever the skip is moved by the cable.

4. The combination stated in claim 3, having the connections between the skip and support so related that the arc through which the skip moves is greater than that through which the support is moved.

5. The combination with a supporting frame and a pivoted loading skip united thereto, of a cable by which the movements of the skip are controlled, a winding mechanism for the cable upon the frame, a stiffleg pivotally supported on the frame and extending above the skip, and idler pulley supported at the upper end of the stiffleg and across which the cable passes, and a link pivoted at one end to the stiffleg, and at the other end having pivotal connection 115 with the skip.

6. The combination stated in claim 5 when the stiff legs are duplicated, one being on each side of the skip, and the connecting links are duplicated, one being associated 120

with each stiff leg and extending to a side of the skip.

7. The combination with a supporting frame and a loading skip having a discharge spout and a loading hopper to the rear of the spout, the skip being pivotally supported upon the frame adjacent to its spout portion, of a cable controlling the movements of the skip, a winding drum upon the frame by which the cable is controlled, a stiffleg pivotally supported on the frame at a point in rear of the pivotal support of the skip, a guide over which the cable passes carried by the stiffleg and located above the upper portion of the skip, and a link having pivotal connection with the stiffleg and

with the skip, the latter connection being in advance of the pivot of the stiffleg and to the rear of the pivot of the skip.

8. The combination with a supporting frame and a loading skip pivotally united thereto, of a stiffleg pivoted to the frame, a rigid connection pivotally uniting the stiffleg and the skip arranged to cause the two united parts to move simultaneously and in the same general direction, a cable for controlling the movements of the stiffleg and skip, and a winding mechanism for the cable.
